US00D511640S

(12) United States Design Patent (10) Patent No.: US D511,640 S
(45) Date of Patent: * Nov. 22, 2005

(54) CHARCOAL GRILL

(75) Inventors: Mike Nipke, Grandville, MI (US);
Carlos Rodriguez, Hudsonville, MI (US)

(73) Assignee: Vendor Development Group, Inc.,
Grand Rapids, MI (US)

() Term: 14 Years

(21) Appl. No.: 29/193,874

(22) Filed: Nov. 14, 2003

(51) LOC (8) Cl. 07-02

(52) U.S. Cl. D7/337

(74) Attorney, Agent, or Firm—McAndrews, Held & Malloy, Ltd.

(57) CLAIM

We claim the ornamental design for a charcoal grill, as shown and described.

DESCRIPTION

FIG. 1 is a perspective view of a charcoal grill showing our new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.
